(57) **CLAIM**

The ornamental design for a foam roller as shown and described.

DESCRIPTION

FIG. 1 is a top perspective view of the foam roller embodied in the present invention;

FIG. 2 is an end view of the foam roller from FIG. 1;

FIG. 3 is a top view of the foam roller from FIG. 1;

FIG. 4 is a bottom view of the foam roller from FIG. 1;

FIG. 5 is a side view of the foam roller from FIG. 1;

FIG. 6 is a top perspective view with break lines of the foam roller from FIG. 1;

FIG. 7 is a top view with break lines of the foam roller from FIG. 1;

FIG. 8 is a bottom view with break lines of the foam roller from FIG. 1; and,

FIG. 9 is a side view with break lines of the foam roller from FIG. 1.

The broken lines in the drawings depict a symbolic break that forms no part of the claimed design. The area between the lines forms no part of the claimed design.
